UNITED STATES PATENT OFFICE.

ANDREW H. RUSSELL, OF WATERTOWN, MASSACHUSETTS.

SIGHT FOR ORDNANCE.

SPECIFICATION forming part of Letters Patent No. 257,077, dated April 25, 1882.

Application filed July 30, 1881. (No model.)

To all whom it may concern:

Be it known that I, ANDREW H. RUSSELL, of Watertown, in the county of Middlesex and State of Massachusetts, have invented certain new and useful Improvements in Gun-Sights, of which the following is a full, clear, and exact description.

In the discharge of guns, as heretofore generally practiced, the sight is directly through the rear and front sights at the object, which obviously necessitates a greater or less exposure of the gunner.

The object of this invention is to secure greater safety to the person of the gunner in sighting the gun, and to enable him to place and keep himself at such time practically behind and below the breech, and thus with the breech of the gun as a protector against exposure and danger.

The invention consists, in substance, in the combination, with the front and rear sights of a gun, of reflecting-surfaces, arranged together upon a common holder, adapted to be moved in a vertical direction and fastened in position, said holder being provided with marks or graduations, the rear sight being located upon or in connection with said holder, and arranged to be stationary or adjusted laterally thereon, all substantially as hereinafter described and shown.

In the accompanying plate of drawings, illustrating my improvements in gun-sights, Figure 1 is a side elevation of a gun provided with reflecting-surfaces in accordance with this invention, which reflecting-surfaces, as shown in the view, are two in number and separate from each other. Fig. 2 is an end view at the breech end of the gun of Fig. 1. Fig. 3 is a side elevation, in diagram, illustrating the reflecting-surfaces as used without the front and rear sights, and the gun as provided with prismatic reflecting-surfaces and with a telescope; Fig. 4, a similar view to Fig. 3, illustrating sight-points as used in lieu of a telescope, as in Fig. 3; Fig. 5, an elevation of the reflecting-surfaces of Fig. 1 in a plane parallel to the axis of the gun; Fig. 6, a sectional view of the reflecting-surfaces of Fig. 1; Fig. 7, an elevation at rear, and Fig. 8 an elevation at front side of same.

In the drawings, A represents a gun sup-

ported on a carriage, B, and both of any suitable style and construction.

a is the front sight attached to the gun, and b the rear sight attached to a holder, C, through which it is secured to the gun, so as to be raised and lowered at pleasure in a direct line vertical to the central longitudinal axis of the gun, according to regular established graduations corresponding to the degrees of elevation of the gun to be obtained, such graduations being shown more particularly in Fig. 5 at S. The rear sight is also arranged to be moved sidewise, or, in other words, in a direction across said axis of the gun, according to regular established graduations to the degrees of horizontal inclination in the direction of the gun to be obtained to allow for drift and wind, all as ordinarily in gun-sights. In the present instance the rear sight is attached to the holder by its two arms o o, extending over the edge p of holder, on which it can slide laterally, as desired, and yet hold the sight firm against accidental displacement. It can, however, be arranged to be secured, when adjusted, in any well-known ways, such as by a set-screw, &c.

d and f are mirrors or reflecting-surfaces made of any suitable material. These reflecting-surfaces are attached to and carried by the holder for the rear sight, b. They are located the one above the other, with an open space, g, between them, and in the direction of the length of the gun, and both surfaces are at an acute angle of twenty-two and one-half degrees or thereabout to each other, and at an obtuse angle to the forward portion of the longitudinal axis of the gun. The two reflecting-surfaces are back of the rear sight, and, as shown in Figs. 1, 2, 5, 6, 7, and 8, they are in two separate parts, whereas in Figs. 3 and 4 they are in one piece in the form of a prism. The front and rear sights are reflected from the lower to and against the upper reflecting-surface, as also the object, and the line of sight from the eye is directed to said upper reflecting-surface at a vertical angle of forty-five degrees or thereabout, and when such reflections of all of these things—to wit, the front and rear sights and the object—coincide upon the upper reflecting-surface the gun is sighted in so far as such coincidence is concerned, it being of course perfectly understood that oth-

erwise in sighting the gun is previously manipulated in the usual mode to provide for distance, drift, and wind. This sighting with reflecting-surfaces, as above described, is independent of any guiding means for the line of sight from the eye to the upper reflecting-surface. Such guiding means, however, may be used, if so desired, and as illustrations thereof of a telescope (shown in Fig. 3) or two separate sights, as shown in Fig. 4, may be used. These sight-guides for the line of sight of the eye preferably are arranged to be adjusted as to their angle of inclination, and when sight-guides are used the rear and front sights of the gun may be dispensed with.

It is preferable to arrange the two reflecting-surfaces *d f*, when separate and distinct from each other, so that the opening between them at their front end may be adjusted as to its width in a vertical direction, and to accomplish this result through and with the upper one only. Such an arrangement is shown in Fig. 5, and consists in hinging the reflecting-surface *d*, at its rear end, to the holder or support *C*, and adapting its front end by a screw-bolt, which passes through a slot in the holder and a screw-nut on such bolt, to be fastened against movement when adjusted.

Reflecting-surfaces for sighting, as herein described, obviously may be used without either of the sights when a telescope or other guide for the line of sight from the eye is employed, and this invention, as to such surfaces broadly, is not to be limited in its use.

The combination, with the reflecting-surfaces, of a telescope or other guide for the line of sight from the eye to the upper reflecting-surface, while it has been herein described, as also the prismatic form of reflecting-surface, constitutes another invention, and one which it is intended hereafter to protect by a separate application for Letters Patent of the United States, and a description of the above is herein given for the purpose of better illustrating the scope of adaptation of my arrangement of

reflecting-surfaces. Reflecting-surfaces arranged substantially as herein described obviously enable the gunner, when sighting the gun, to place himself behind and below the breech, and thus greater protection of the person is secured.

The holder for the reflecting-surfaces and rear sight is arranged to be moved in a direct line through a collar, *k*, attached to a pin, *l*, which sets into a socket, *m*, of the gun, and the holder is fastened rigidly in position by a thumb-screw, *n*, which screws into the collar and against the holder. This arrangement of the holder also enables it to be adjusted in a vertical direction to be swung around, and to be removed at pleasure, all substantially as ordinarily with the rear sight of the gun.

The rear sight, in lieu of being attached directly to the holder *C*, can be marked or indicated in any well-known way upon one of the reflecting-surfaces, preferably the lower one. This means of attaching the sight-holder secures an important advantage, in that the sight can be accurately adjusted or set to its required height and afterward placed on the gun by the pin and socket-joint attachment, which is of convenience.

Having thus described my invention, what I claim, and desire to secure by Letters Patent, is—

The combination, with a gun provided with sights *b a*, of the reflecting-surfaces *d f*, carried, together with the rear sight, by a common holder adapted to be moved vertically and fastened in position, the rear sight, *b*, being arranged to move and be adjusted laterally on said holder, all substantially as and for the purpose specified.

In testimony whereof I have hereunto set my hand in the presence of two subscribing witnesses.

A. H. RUSSELL.
